UNITED STATES PATENT OFFICE

1,938,027

CAR DUMPER

Elwin H. Kidder, Chicago, Ill., assignor to Link-Belt Company, Chicago, Ill., a corporation of Illinois

Application June 1, 1931. Serial No. 541,382

20 Claims. (Cl. 214—47)

My invention relates to a grain car unloader and has for one purpose the provision of unloading means whereby a car filled with grain can quickly and efficiently be unloaded. Another purpose is the provision of door opening means for such a grain car unloader and, particularly, door opening means which will operate, when the grain car is tilted laterally, to press in the car door and to permit the grain to escape. Another object is the provision of means for holding the grain car door out of the line of grain flow after it has been opened. Other objects will appear from time to time in the course of the specification and claims.

15 I illustrate my invention more or less diagrammatically in the accompanying drawings, wherein—

Figure 1 is a side elevation, with parts in section;

20 Figure 2 is an end elevation of the parts prior to the car door being opened;

Figure 3 is an end elevation with parts in section, illustrating the opening device in position at the end of the grain car door opening movement.

Figure 4 is a partial top plan view of one side of the platform structure and associated parts;

Figure 5 is an enlarged section along the line 5—5 of Figure 1; and

30 Figure 6 is a section along the line 6—6 of Figure 5.

Like parts are indicated by like symbols throughout the specification and drawings.

Referring to the drawings, A generally indicates 35 the bottom of any suitable pit, provided with walls A¹. A² indicates a projection or bracket extending inwardly from one of said walls upon which some of the car handling mechanism below described may be positioned. A³ generally 40 indicates a receiving hopper with the bottom A⁴ and the discharge aperture A⁵ which may be closed as by any suitable removable closure members A⁶. A⁷ indicates a conveyor belt upon which the grain discharged through the apertures A⁵ 45 may be received and conveyed for disposal elsewhere.

B B indicate base members herein shown as positioned upon the bottom A of the pit, and supporting any suitable frame B¹. B² indicates 50 any suitable motor, for example an electric motor which drives a gear train including the motor shaft pinion B³ in mesh with gear B⁴ which by means of an associated pinion drives the gear B⁵ which in turn rotates the pinion B⁶ in mesh 55 with the gear B⁷. Associated with the gear B⁷ is

any suitable drum B⁸ about which pass the cables B⁹ B¹⁰.

C C indicate rollers, pivoted upon the frame B¹. These are channeled as at C¹ to receive the arcuate track C². This track is mounted upon any suitable supporting frame work generally indicated as C³, upon which in turn is mounted any suitable platform structure C⁴ which may have positioned upon its top the track rails C⁵. The cables B⁹ are dead ended or secured, at their ends, at opposite ends of the tracks C², as at C¹¹ C¹², for example in stop members C¹² which serve, by contact with the rollers C, to limit the possible tilt of the platform or cradle structure above described. It will be understood that when the cradle or platform is in the position in which it is shown in Figures 2 and 4, the ends of the platform C⁴ are positively supported. I indicate for example supporting abutments C⁶ for the left side of each end of the platform, and supporting abutments C⁷ for the right side of each end of the platform, the supporting abutments C⁷ being farther from the mid point of the platform than the abutments C⁶, the platform being forwardly extended as at C⁸, in order to engage and rest upon the abutments C⁷. It will therefore be understood that when the parts are in the position in which they are shown in Figures 2 and 4, any longitudinal tilting of the platform is positively prevented by the abutments upon which it rests, and with which, in effect, the platform interlocks. As shown in Figure 2 it will be noted that the abutments C⁶ are provided with convex upper surfaces which rest in corresponding concave surfaces C⁹ of the blocks C¹⁰ upon the lower portion of the ends of the frame.

D D indicate any suitable clamps for the ends of the car generally indicated as D¹ and positioned, when inoperative, in the pits D¹¹. They may include pads or abutment members D² opposed to the couplings D³ of the car, and any suitable means may be employed for raising and drawing the clamps D into operative position when it is desired to secure a car in place upon the platform. As the details of the clamping mechanism do not of themselves form part of the present invention, they are diagrammatically illustrated. I may for example employ a motor D⁴ mounted on the platform C⁴ which drives the shaft D⁶ through the gear reductions generally indicated as D⁵. The shaft D⁶, through the gear reductions D⁷, drives the nut D²⁰ which moves the screw D⁸ longitudinally. D⁹ indicate tracks along which the carriages D¹⁰ may move into and out of operating position for the con-

veyance of the clamps D into and out of operative position.

Extending upwardly from one side of the platform C⁴ is a bracket frame E which supports an 5 upstanding frame structure generally indicated as E¹, which includes the transverse top structural member E². Pivoted adjacent or upon the trans- 10 verse member E² is a hanger structure indicated as E³, which may be pivoted as at E⁴. At its 15 lower end is a guide E⁵ upon which is adjustably or slidably mounted the door engaging member E⁶, which may for example have a plate pro- 20 vided with the forward spikes or projections E⁷. Any suitable means may be employed for raising 25 and lowering the door contacting member E⁶. I may employ for example the cable E⁸ passing about a sheave E⁹ and about a shaft E¹⁰, the rotation of which may be controlled as by the lever E¹¹ and ratchet wheel E¹² and the dogs E¹³, E¹⁴. The dog E¹³ is mounted on the lever E¹¹ and serves to rotate the ratchet, while the dog E¹⁴ is mounted on the hanger and serves to prevent unintended retrograde rotation of the ratchet. However, any other suitable means for 25 raising or lowering the member E⁶ may be employed.

Mounted on the platform A² is the unitary frame G upon which is mounted any suitable motor G¹ which drives, through its motor shaft 30 pinion G², a gear G³ upon the shaft G⁴, the pinion G⁵ of which is in mesh with a gear G⁶ which is mounted on a threaded sleeve G⁷, the rotation of which actuates the screw G⁸, to impart longitudinal or axial movement thereto. G⁹ 35 generally indicates a universal joint or universal coupling for the opposite end of the screw G⁸. I do not wish to be limited to any specific universal joint, but I have shown a block G¹⁰ on the end of the screw G⁸ to which is pivoted a yoke G¹¹ 40 to which in turn is pivoted another yoke G¹², which in turn is connected to a rod G¹³ which is connected by a similar universal connection at its opposite end to the upright frame structure E¹, as upon the horizontal longitudinal plate E¹⁴. It will be understood that as the motor G¹ 45 is actuated the rotation of the sleeve G⁷ im- parts axial longitudinal movement to the screw G⁸ and thus moves the platform or cradle structure as a whole toward or away from the bracket E¹⁴. It will be understood that as the car dumper 50 platform C⁴ is supported upon the track C² which in turn is supported upon the rollers C, seating in the grooves C¹ of said rollers. It will be seen, as in Figures 2 and 3, that when the rails C⁵ on 55 the platform C⁴ are aligned with the rails C²⁰ of the track ends, the frame structure C³ is tilted to the left, referring to the position of the parts as in Figure 2, and that the weight of the structure thus tends to hold the platform C⁴ firmly 60 in position upon the supporting abutments C⁶. Any additional locking means may be employed if desired, but the structure is normally grav- 65 itally held in position. On the other hand, when it is desired to tilt the car longitudinally and the parts are moved into the position in which they are shown in Figure 3, the frame structure C³ lies in a generally vertical plane.

H indicates any suitable deflector whereby grain discharged from the car D¹ may be delivered into the bin A³.

It will be understood that it is current practice to nail inner grain car doors within the normal doors of the freight cars in which grain is shipped. The permanent freight car doors, 75 which are not indicated herein, being slid or

moved out of alignment with the door opening, there are still left the boards J of the grain door, which may for example be nailed at the inside of the door aperture. When the car is tilted laterally into the position in which it is shown in Figure 3, the members E⁶ and E⁷ must be moved forwardly against the grain door. In order to effect this movement I provide a compression member J¹ which is connected at one end, by means of a universal joint J² to the hanger structure E³. At its other end it is connected as by the universal connection J³ with any suitable cover or housing J⁴ which forms part of or is secured to the unitary structure generally indicated as G. It will therefore be understood that as the car structure is tilted laterally to the position of Figure 3, the member J¹ serves as a compression member to prevent the complete unitary movement of the members E⁶ and E⁷ with the car. As the car and car support C⁴ tilt, the hanger E³ is forced to pivot about its axis E⁴. This first engages the member E⁶ with the door boards J, and then forces them into the position shown in Figure 3. Points E⁷ normally hold the door boards J in place as a unit and entirely out 100 of alignment with the escaping grain.

In the operation of the device a car is first spotted on the platform C⁴. The clamps D are then actuated to hold it in place, the motor G¹ is then actuated to draw in on the member G¹³ 105 which then serves as a tension member to tilt the frame C³ and the platform C⁴ laterally about a pivot defined by the rollers C. However, this lateral tilting movement causes the member J¹ to serve as a compression member and to force the door boards J into the position in which they are shown in Figure 3 as above described. The motor B² may then be actuated to tilt the car longitudinally, and the grain pours out through the car door and upon the deflector H and into 115 the bin A³. Any suitable means may be employed for assisting the escape of the grain, such baffles or the like, such means not herein indicated as not forming of themselves part of the present invention. When the car has been finally 120 cleared of its grain it may then be rotated back to the position in which it is shown in Figure 1 with the result that the door opener is also re- 125 turned to the position in which it is shown in Figures 1 and 2. The clamps D can then be moved into inoperative position and the car removed along the rails C²⁰.

It will be realized that whereas I have de- 130 scribed and shown a practical and operative de- vice, nevertheless many changes may be made in size, shape, number and disposition of parts without departing from the spirit of my inven- 135 tion. I therefore wish the drawings and de- scription to be taken as in a broad sense illus- trative or diagrammatic rather than as limiting me to my specific showing herein.

Attention is called to the fact that because the cradle in the upright position rests at its ends upon fixed supports and is substantially entirely supported by them, no interlocking means are 140 needed to maintain the cradle against displace- 145 ment as cars run onto and off of it, and up to the time when the cradle is laterally tilted the bridge or cradle is as rigid and fixed in position, without any interlocking or special latch means, as if it were an integral part of the track structure, and it is only when the lateral tilting means have gone into operation, lifted the cradle off its supporting abutments and moved it lat- 150 erally to bring the interlocking parts on the

cradle out of line with the supporting pads on the abutments, that endwise tilting of the cradle becomes possible. Thus the lateral tilting means serve both to tilt the car so as to insure that the grain will run out of the side, and also to position and interlock the car cradle with the structure, thereby obviating any necessity of any positive movable interlocking means.

Because the roller ring with its arcuate track

10 engages the supporting rollers in the bottom of the pit and may both travel along those rollers and rotate in a plane parallel with their axes, no separate supporting means are provided, and because the endwise tilting cable wound about 15 the roller ring is connected to the driving drum at a point between the two rollers and adjacent the line joining the points of contact between each roller and the roller ring, the lateral tilt of the cradle does not materially affect the length 20 of the cable, so no special adjustment is needed.

Of course the roller ring cannot have its traveling movement along the rollers unless it is located in a plane substantially perpendicular to their axes of rotation, and it only reaches this 25 position when the cradle has been tilted. This is a real advantage because automatically there is an interlock in that as long as the roller ring is in such position that it cannot travel along the rollers, the cradle is interlocked with its supporting 30 abutments. When the cradle has been finally tilted out of that interlock relation, the roller ring is, at the same time and by the same movement, brought into a position where it is free to travel along the rollers.

35 It will also be noted that the axis about which the whole structure rotates for endwise tilt is substantially on line with the fixed abutment so that the universal joint connection between the threaded sleeve on the abutment and the cradle 40 is sufficient to permit the endwise tilt of the cradle and car without interference.

I claim:

1. A car unloader comprising a cradle adapted to carry a track, and means for holding a car in 45 spotted position thereon, supporting abutments for said cradle adapted to hold the cradle in interlocked relation, a tilting support for the cradle, means for operating said tilting support to laterally displace the cradle and simultaneously break the interlock between the cradle and its abutment, and means, operative only after the cradle has been laterally tilted and the interlock broken, for tilting the cradle longitudinally.

55 2. A car unloader including a cradle, an arcuate supporting structure integral therewith, rollers in operating relation with the periphery of the arcuate supporting structure, means, applied at the center of rotation of the rotating structure, for tilting it laterally, means, applied at the periphery of the arcuate structure and substantially on a line with its axis of lateral rotation, for rotating it longitudinally and power means 60 for operating said rotating means, said power means being fixed in position with respect to the supporting rollers.

65 3. A car unloader including a cradle, an integral supporting structure extending downwardly therefrom, a semi-circular track bounding such structure, the center about which the track is described being located adjacent the floor of a car carried on the cradle, supporting rollers upon which the track rests, means in fixed position with respect to the rollers at one side of the structure for tilting it laterally about an axis 70 joining the points of contact between said rollers

and the track, and a connection between the structure and such tilting means applied thereto adjacent the center of rotation, means for rotating the structure to cause the track to travel along the rollers, said means being in fixed position with respect to the rollers, and a connection between such rotating means and the structure localized at a point adjacent the track and between the rollers.

4. In a car unloader, a cradle and means for 80 positioning a car thereupon, an arcuate edged support for the cradle, means for moving said cradle laterally, and means for tilting said cradle longitudinally, when laterally moved, the means for moving the cradle laterally including a member connected to the cradle and extending transversely therefrom, located substantially at the center about which the arcuate edge of the support is described, and means for applying force to said member to move the cradle.

5. In a car unloader, a cradle and means for 85 positioning a car thereupon, an arcuate edged support for the cradle, means for moving said cradle laterally, and means for tilting said cradle longitudinally, when laterally moved, the means for moving the cradle laterally including a member connected to the cradle and extending transversely therefrom, located substantially at the center about which the arcuate edge of the support is described, and means for applying force to said member to move the cradle, and a flexible 90 connection between said member and the cradle.

100 6. In a car unloader, a cradle and means for positioning a car thereupon, an arcuate edged support for the cradle, means for moving said cradle laterally, and means for tilting said cradle longitudinally, when laterally moved, the means for moving the cradle laterally including a member connected to the cradle and extending transversely therefrom, located substantially at the center about which the arcuate edge of the support is described, and means for applying force to 105 said member to move the cradle, and a universal joint connection between said member and the cradle.

110 7. In a car handling device, a track, a cradle adapted to be aligned with said track, means for positioning a car on the cradle, supporting means for supporting the cradle when aligned with the track, and additional supporting means for the 115 cradle, effective when the cradle has been laterally moved, means for laterally tilting the cradle, the center of support of said last mentioned supporting means being laterally removed from the central axis of the track in the direction toward 120 which the cradle is tilted, the weight of car and cradle tending, at all positions of said support, to return the cradle to alignment with the track, and means for longitudinally tilting the cradle when it has been moved out of longitudinal 125 alignment with the track.

130 8. In a car handling device, a track, a cradle adapted to be aligned with said track, means for positioning a car on the cradle, supporting means for supporting the cradle when aligned with the track, and additional supporting means for the 135 cradle, effective when the cradle has been laterally moved, means for laterally tilting the cradle, the center of support of said last mentioned supporting means being laterally removed from the central axis of the track in the direction toward which the cradle is tilted, the weight of the car and cradle tending, at all positions, to return the cradle to alignment with the track, and means for longitudinally tilting the cradle when it has 140 145 150

been moved out of longitudinal alignment with the track, said supporting means including an arcuately edged support and supporting rollers adapted to receive it.

9. In a car handling device, a track, a cradle adapted to be aligned with said track, means for positioning a car on the cradle, supporting means for supporting the cradle when aligned with the track, and additional supporting means for the cradle, effective when the cradle has been laterally moved, means for laterally tilting the cradle, the center of support of said last mentioned supporting means being laterally removed from the central axis of the track in the direction toward which the cradle is tilted, the weight of car and cradle tending, at all positions, to return the cradle to alignment with the track, and means for longitudinally tilting the cradle when it has been moved out of longitudinal alignment with the track, said additional supporting means including an arcuately edged support and supporting rollers adapted to receive it, and means for laterally tilting the cradle including an actuating connection with the cradle adjacent the center of the arc of the edge of the support.

10. In a car unloader, a track, a cradle adapted to be aligned with said track, means for positioning a car upon said cradle, means for moving said cradle laterally out of alignment with said track and for tilting said cradle when laterally so moved, said cradle including side members of unequal length, the side member on the side of the cradle towards which the cradle laterally tips being of greater length than the opposite side member.

11. In a car unloader, a track, a cradle adapted to be aligned with said track, means for positioning a car upon said cradle, means for moving said cradle laterally out of alignment with said track and for tilting said cradle when laterally so moved, said cradle including side members of unequal length, the side member on the side of the cradle towards which the cradle laterally tips being of greater length than the opposite side member, and cradle supports, operative when the cradle is aligned with the track, underlying said side members, the supports which underlie the longer of the side members being separated by a distance greater than the length of the shorter side member.

12. In a car unloader, a cradle adapted to support a car, a downwardly projecting supporting member rigidly associated with the cradle and a fixed abutment upon which said cradle rests, means for tilting the cradle and rigid member laterally in the same direction and for tilting them longitudinally, and means for positively preventing the longitudinal tilting movement until the lateral tilting movement has been completed.

13. In a car unloader, a cradle adapted to support a car, a downwardly projecting supporting member rigidly associated with the cradle, means for tilting the cradle and rigid member laterally and for tilting them longitudinally, and means for positively preventing the longitudinal tilting movement until the lateral tilting movement has been completed, said means comprising fixed abutments on which the cradle is positively supported at the beginning of the lateral tilting movement.

14. In a car unloader, a cradle adapted to support a car, a downwardly projecting supporting member rigidly associated with the cradle, means

for tilting the cradle and rigid member laterally and for tilting them longitudinally, and means for positively preventing the longitudinal tilting movement until the lateral tilting movement has been completed, said means comprising fixed abutments on which the cradle is positively supported at the beginning of the lateral tilting movement, the abutments being so positioned with respect to the cradle that the lateral tilting movement carries the cradle out of line with the abutments to permit the longitudinal tilt.

15. In a car unloader, a cradle, a segmental roller ring integral therewith and projecting downwardly therefrom, a pair of rollers adapted to engage the periphery of the roller ring and support it, a car track carried by the cradle, the roller ring being inclined to the vertical when the car track is horizontal, means for tilting the roller ring about an axis joining the points of contact of the two rollers and the ring to bring the roller ring into a substantially vertical plane.

16. In a car unloader, a cradle, a segmental roller ring integral therewith and projecting downwardly therefrom, a pair of rollers adapted to engage the periphery of the roller ring and support it, a car track carried by the cradle, the roller ring being inclined to the vertical when the car track is horizontal, means for tilting the roller ring about an axis joining the points of contact of the two rollers and the ring to bring the roller ring into a substantially vertical plane, and means for rotating the roller ring about an axis parallel with the axis of the rollers when in such vertical plane.

17. In a car unloader, a cradle, a segmental roller ring integral therewith and projecting downwardly therefrom, a pair of rollers adapted to engage the periphery of the roller ring and support it, a car track carried by the cradle, the roller ring being inclined to the vertical when the car track is horizontal, means for tilting the roller ring about an axis joining the points of contact of the two rollers and the ring to bring the roller ring into a substantially vertical plane, the tilting means being connected to the cradle at a point substantially concentric with the roller ring.

18. In a car unloader, a cradle, a segmental roller ring integral therewith, and projecting downwardly therefrom, a pair of rollers adapted to engage the periphery of the roller ring and support it, a car track carried by the cradle, the roller ring being inclined to the vertical when the car track is horizontal, means for tilting the roller ring about an axis joining the points of contact of the two rollers and the ring to bring the roller ring into a substantially vertical plane, and means for rotating the roller ring about an axis parallel with the axis of the rollers when in such vertical plane, the lateral tilting means being connected to the cradle at a point substantially concentric with the roller ring, the power to cause longitudinal tilting being applied at a point adjacent to the line joining points of contact of the two rollers and the roller ring.

19. In a grain car unloader, a track section, a fixed abutment upon which the track section is supported when in horizontal position, means for securing a grain car at a predetermined point upon said track section, means for bodily displacing the track section laterally to disengage it from the abutment, means for longitudinally tilting the track section after it has been so disengaged, the abutment and track section being in interlocking relation whereby longitudinal tilting is positively

prevented until the lateral displacement has been completed.

20. In a car dumper, a track section, two separate independent supporting means therefor spaced apart and out of contact with one another, one means operative exclusively when the track section is in line with the remainder of the track, the other operative as a supporting means exclu-

sively only when the track section is out of line with the remainder of the track, and means for tilting the track section laterally to clear the first named track supporting means and means operative only after such lateral tilt to tilt the track section longitudinally. 80
